SPACE HEATER

Stephen N. Bobo, New York, N. Y., assignor to
Robert P. Sniffen, New York, N. Y.

Application November 22, 1939, Serial No. 305,602

5 Claims. (Cl. 126—92)

My present invention relates to heating apparatus, and more particularly to an improved radiant heater of the reflector type.

In carrying out my invention I preferably employ a stand having the reflecting portion in the form of an upright substantially cone-shaped member, the reflecting surface being in the form of a cylindrical member generated by the revolution of a parabolic curve about an axis of rotation. While the reflecting surface is parabolic in form, it is not necessarily cylindrical, as obviously within the scope of my invention I may make up the reflecting surface of a plurality of separate, independent, parabolically shaped faces. The reflecting surface being in the form substantially that of a cone, I position at the apex, or the portion adjacent to the apex of such cone, a heating element comprising a plurality of glow points arranged on the lower surface of a heat reflector of preferably ceramic or other heat resisting material which directs the heat produced by a burner of gaseous material downwardly onto the parabolic reflecting surface. The entire apparatus is portable in nature and may be moved from place to place in any enclosure desired, such as a room, hall or the like.

The principal object of my invention therefore is an improved radiant heater of the reflector type.

A feature of my invention is an improved heater having a parabolic surface in combination with a reflecting heating element which reflects heat downwardly onto the parabolic surface.

Another feature of my invention is an improved radiant heater in which heat is radiated parallel to the support for the heater.

A still further feature of my invention is an improved radiant heater of the reflector type in which the major portion of the heat generated is reflected outward at right angles to the axis of the heater and a portion of the heat generated passes upwardly from the burner of the device.

Other novel features of the invention will appear as the description thereof progresses.

In the accompanying drawings:

Fig. 1 is a vertical sectional elevation of a heater embodying my invention.

Fig. 2 is a sectional plan view on the line 2—2 looking in the direction of the arrows, and

Fig. 3 is a sectional plan view taken on the line 3—3 of Fig. 1 and looking in the direction of the arrows.

Referring to the drawings, 10 designates a heat reflecting element, generally of frustro-conical

form, and the curvature of which is parabolic. Secured to, though preferably formed integral therewith, is a depending skirt portion 11. The upper smaller diameter end of the reflector 10 is recessed at 12 to provide a supporting seat or shelf for a burner 13. Such burner 13 is preferably one adapted to burn gaseous fuel and is circular in plan view as shown in Figure 2.

The skirt 11 and reflector 10 are preferably formed integral with each other and are of sheet metal and stamped or spun to the shape required. The lower end of the depending skirt portion 11 is open, as shown, and is provided at various points about its periphery with projections 14 having feet 15 attached thereto and by means of which the elements 10 and 11 are raised above the support on which the feet 15 rest.

The burner 13 is provided with a plurality of radially extending perforations 16 through which the gaseous fuel flows under the usual pressure and thus directs the flame horizontally over a designated area. The lower end of the burner 13 is machined to receive the upper open end 17 of a gas tuyère 18, a felt or other compressible washer 19 being utilized to insure a gas-tight joint between the burner 13 and tuyère 18.

The lower end of the tuyère 18 is provided with a mixing chamber 20 and the end of the chamber 20 is provided with a grating 21. Rotatably mounted on the lower end of the mixing chamber 20 is a perforated member 22 which cooperates with the openings in the grating 21 to regulate the flow of air to the mixing chamber 20. The grating 21 is perforated to receive the delivery end 23 of a gas feed pipe 24, the adjustment of the end 23 of the gas feed pipe 24 with respect to the mixing chamber 20 being controlled by the nut 25. The gas feed pipe 24 is connected through pipe 26 and valve 27 to a suitable source of fuel supply.

Extending upwardly and about the periphery of the reflector element 10 are spaced standards or supports 28. The lower ends of these supports 28 extend downwardly through the reflecting element 10 and terminate at the brackets 14 as shown in Fig. 1. At the upper ends of the standards 28 is secured a cylindrical member 29. The cylindrical member 29 is secured to the standards 28 in any desired way as by riveting, soldering, spot welding or the like, and the cylindrical member 29 is positioned so as to enclose the upper end of the reflecting element 10 and the burner 13 as clearly shown in Fig. 1. Within the cylindrical member 29 is arranged a shelf or ledge

30 which forms a support for a ceramic glow element 31.

This glow element 31 is made up of a plurality of sections 32, preferably of ceramic material, or other suitable non-combustible material. The sections 32 have a depending skirt portion 33 which rests on the shelf or ledge 30 and maintains the body portion 34 slightly above the upper end of the burner 13. The under face of the body portion 34 is provided with a plurality of spaced downwardly extending glow points 35, and the body portion 34 between such points 35 is provided with a plurality of perforations 36. The sections 32 when in assembled position define a centrally located passageway 37 through which air may flow to serve as means to maintain the burner 13 in relatively cool condition.

Fitting over the upper peripheral edge of the cylindrical member 29 is a dome shaped cover 38 which is provided with an inwardly projecting ledge 39 which engages the topmost edge of the cylindrical member 29. The dome 38 is provided with an opening 40 at the top, and into such opening fits a removable cover 41, such covering being provided with a handle 42 and by means of which the cover may be placed in or removed from the opening 40 in the dome 38.

When the valve 27 is rotated to permit flow of gaseous fuel through the pipes 26 and 24 into the tuyere 18 and into the burner 13, the same may be ignited in the usual manner and the flame from the burning gas is ejected horizontally and into engagement with the glow points 35. The heated points radiate or throw the heat downwardly into engagement with the reflector 10, and such heat will be reflected or radiated outwardly from the reflector 10 in a horizontal direction. By removing the cover 51 there will be a considerable amount of heat passed upwardly through the opening 40 without detracting appreciably from the amount of heat delivered to the reflector 10.

The device is portable and may be carried to any desired place in a room or apartment, and is economical in that every bit of heat generated is rapidly thrown out and thrown out in a direction to produce the best results. The reflecting element 10 is preferably cylindrical in cross section as shown in Figure 3 for example but obviously this is a matter of design only, and I may make the reflecting element of a plurality of sectors to thereby produce a multi-sided reflector, but one which in the main is substantially of frustro-conical form as shown in Figure 1. I believe however that the reflecting element which is circular in cross-section is the most efficient form and I have therefore shown the same in the drawings.

Whereas I have described my invention by reference to specific forms thereof, it will be understood that many changes and modifications may be made without departing from the spirit of the invention.

I claim:

1. In an improved heating apparatus, the combination of a heat reflecting element of substantially frustro-conical form and having its surface generated by the revolution of a parabola about an axis of rotation, an opening formed in the apex of the heat reflecting element, a shelf formed of the material of the heat reflecting element and about the periphery of the opening therein, a gaseous fuel burner mounted on such shelf, means for supplying gaseous fuel to the burner, said burner constructed to eject gaseous

fuel radially outward from the burner, a heat radiating member of non-combustible material mounted about the burner and provided with a plurality of downwardly extending glow points, said non-combustible element directing heat from the glow points downwardly onto the parabolic heat reflecting surface.

2. In an improved heating apparatus, the combination of a heat reflecting element of substantially frustro-conical form and having its surface generated by the revolution of a parabola about an axis of rotation, an opening formed in the apex of the heat reflecting element, a shelf formed of the material of the heat reflecting element and about the periphery of the opening therein, a gaseous fuel burner mounted on such shelf, means for supplying gaseous fuel to the burner, said burner constructed to eject gaseous fuel radially outward from the burner, a heat radiating member of non-combustible material mounted above the burner and provided with a plurality of downwardly extending glow points, said non-combustible element directing heat from the glow points downwardly onto the parabolic heat reflecting surface, and a plurality of perforations formed in the non-combustible element to permit escape of heated air and gases upwardly through the element.

3. In an improved heating apparatus, the combination of a heat reflecting element of substantially frustro-conical form having its surface generated by the revolution of a parabola about an axis of rotation, an opening formed in the apex of the heat reflecting element, a shelf formed of the material of the heat reflecting element and about the periphery of the opening therein, a gaseous fuel burner mounted on such shelf, means for supplying gaseous fuel to the burner, said burner constructed to eject gaseous fuel radially outward from the burner, a heat radiating member of non-combustible material mounted about the burner and provided with a plurality of downwardly extending glow points, said non-combustible element directing heat from the glow points downwardly onto the parabolic heat reflecting surface, a plurality of perforations formed in the non-combustible element to permit escape of heated air and gases upwardly through the element, and a centrally arranged perforation in the non-combustible element for permitting circulation of air through the element and maintaining the burner at a relatively low temperature.

4. In an improved heating apparatus, the combination of a heat reflecting element of substantially frustro-conical form and having its surface generated by the revolution of a parabola about an axis of rotation, an opening formed in the apex of the heat reflecting element, a shelf formed of the material of the heat reflecting element and about the periphery of the opening therein, a gaseous fuel burner mounted on such shelf, means for supplying gaseous fuel to the burner, said burner constructed to eject gaseous fuel radially outward from the burner, a heat radiating member of non-combustible material mounted above the burner and provided with a plurality of downwardly extending glow points, said non-combustible element directing heat from the glow points downwardly onto the parabolic heat reflecting surface, and a removable hood cover for enclosing the non-combustible heat reflecting element.

5. In an improved heating apparatus, the combination of a heat reflecting element of substan-

tially frustro-conical form and having its surface generated by the revolution of a parabola about an axis of rotation, an opening formed in the apex of the heat reflecting element, a shelf formed of the material of the heat reflecting element and about the periphery of the opening therein, a gaseous fuel burner mounted on such shelf, means for supplying gaseous fuel to the burner, said burner constructed to eject gaseous fuel radially outward from the burner, a heat 10

radiating member of non-combustible material mounted above the burner and provided with a plurality of downwardly extending glow points, said non-combustible element directing heat from the glow points downwardly onto the parabolic heat reflecting surface, a removable hood cover for enclosing the non-combustible heat reflecting element, and a removable cover in said member.

STEPHEN N. BOBO.
